CLAIM

The ornamental design for a portable monitor, as shown and described.

DESCRIPTION

FIG. 1 is a perspective view of a portable monitor in an extended state, showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof;

FIG. 8 is a bottom plan view thereof;

FIG. 9 is a perspective view of the portable monitor of FIGS. 1-8, shown in a collapsed state;

FIG. 10 is an enlarged view of the encircled portion '10' in FIG. 6;

FIG. 11 is an enlarged view of the encircled portion '11' in FIG. 6; and,

FIG. 12 is an enlarged view of the encircled portion '12' in FIG. 6.

The dash-dash broken lines depict portions of the portable monitor that form no part of the claimed design.

The dash-dot broken lines in FIGS. 6, 10, 11 and 12 represent the extents of the enlarged detail views and form no part of the claimed design.

1 Claim, 12 Drawing Sheets
